Primary Examiner — Ricky Pham*(74) Attorney, Agent, or Firm* — Mathew L. Grell; Jeffrey C. Watson; Grell & Watson Patent Attorneys LLC(57) **CLAIM**

The ornamental design for a sport spoon, as shown and described.

DESCRIPTION

FIG. 1 is a perspective view of the sport spoon with the spoon bowl as a basketball ball and the spoon handle as a basketball net showing my design;

FIG. 2 is a top view thereof;

FIG. 3 is a bottom thereof;

FIG. 4 is a front side view thereof;

FIG. 5 is a back side view thereof; and,

FIG. 6 is a left side view, the right side view being a mirror image thereof.

The broken lines shown in FIGS. 1-6 represent the portions of the design which form no part of the claimed design, such as ball seams and net lines.
